UNITED STATES PATENT OFFICE.

HENRY MESINGER AND FREDERICK MESINGER, OF NEW YORK, N. Y.

DESIGN FOR A BICYCLE-SADDLE.

SPECIFICATION forming part of Design No. 25,423, dated April 21, 1896.

Application filed March 13, 1896. Serial No. 583,145. Term of patent 7 years.

To all whom it may concern:

Be it known that we, HENRY MESINGER and FREDERICK MESINGER, subjects of the Emperor of Germany, residing in the city, county, and State of New York, have invented and produced a new and original Design for Bicycle-Saddles, of which the following is a specification, reference being had to the accompanying drawings, showing the parts thereof.

10 Figure 1 is a plan view of a saddle, showing our design; and Fig. 2 is an edge view of the same, these two views being deemed necessary to fully illustrate said design.

The leading feature of our design consists, in brief, of an outline of general pelecoidal shape, having a centrally-disposed opening whose contour is substantially parallel with said outline. Upon the field inclosed by the outline of the said central opening are dis-

15 and diagonally to each other, said lines being interwoven, as shown.

The letter *a* indicates that portion of our design corresponding to the rear end of the saddle, the same being semioval, and from the extreme ends of said semioval portion inwardly-curved lines *b b* extend forward, gradually approaching each other, being finally connected by a substantially semicircular line *c* at the pommel end of the saddle design. 30

The side walls of the said design extend upward and curve inward, as in Fig. 2.

What we claim is—

The design for a bicycle-saddle substantially as herein shown and described.

HENRY MESINGER.

FREDERICK MESINGER.
